CLAIM

The ornamental design for an ammunition magazine, as shown and described.

DESCRIPTION

FIG. 1 is a right-side, bottom perspective view of an ammunition magazine showing my new design.

FIG. 2 is a right-side view of my new design shown in FIG. 1.

FIG. 3 is a left-side view of my new design shown in FIG. 1.

FIG. 4 is a rear view of my new design shown in FIG. 1. FIG. 5 is a front view of my new design shown in FIG. 1. FIG. 6 is a top view of my new design shown in FIG. 1; and, FIG. 7 is a bottom view of my new design shown in FIG. 1. The broken lines in the drawings depict environment that forms no part of the claimed design.
